UNITED STATES PATENT OFFICE.

CHARLES A. FISHER, OF NIAGARA FALLS, NEW YORK, ASSIGNOR OF SEVENTY-THREE ONE-HUNDREDTHS TO LOUIS SILBERBURG, OF NIAGARA FALLS, NEW YORK, AND CURT C. ANDRUS, OF NORTH TONAWANDA, NEW YORK.

CAR-BRAKE.

SPECIFICATION forming part of Letters Patent No. 787,363, dated April 18, 1905.

Application filed May 14, 1904. Serial No. 208,017.

To all whom it may concern:

Be it known that I, CHARLES A. FISHER, a citizen of the United States, residing at Niagara Falls, in the county of Niagara and State of New York, have invented new and useful Improvements in Car-Brakes, of which the following is a specification.

This invention relates to hand-operated car-brakes; and the primary object of the same is to provide a brake of this class with means for positively applying the brake-shoes to the wheels with increased force without imposing extra strain on the motorman or operator and, in fact, reducing the applied force on the brake-staff or analogous device relatively to that usually required to set the brakes.

A further object of the invention is to provide means in a hand-brake for taking up the slack in the connection to the brake-levers controlled by a motorman or other operator and increasing the force proportionately as the power is applied.

The principle of operation embodied in the improved hand-brake is to increase the tension through the connection with the brake-levers relatively to the draft of the elements controlled by a motorman or other operator through the medium of an intermediate controller connected to a brake-staff and the brake-levers, the connection for the latter being arranged in such manner and operating with the controller so as to increase the leverage thereon to an excessive extent and obtain an immediate response both in applying and releasing the brake-shoes without lost motion.

The invention further consists in the construction and arrangement of parts, which will be more fully hereinafter set forth.

In the drawings, Figure 1 is a top plan view of car-trucks, showing the usual brake mechanism applied thereto and illustrating the features of the invention in coöperation therewith. Fig. 2 is a horizontal section on the line 2-2, Fig. 3. Fig. 3 is a sectional elevation of the controller and hanger with which

the brake-staff and brake-lever mechanism are connected. Fig. 4 is a section on the line 4-4, Fig. 3. Fig. 5 is a detail elevation of the lower extremity of the brake-staff. Fig. 6 is a detail enlarged elevation of one of the rollers for the brake-lever connection movably disposed in the controller. Fig. 7 is a top plan view of the controller, showing a modification in the means for increasing the leverage on the brake-lever connection. Fig. 8 is a transverse vertical section of the hanger for the controller and the latter in edge elevation, illustrating a modification in the construction.

Like parts appearing in different illustrations are designated by similar reference notations.

A designates the car-trucks, which are of any approved construction and duplicates of each other, and centrally arranged thereon and firmly secured in position are plates or analogous devices 1, having outwardly-extending projections 2, to which actuating-arms 3 are pivotally connected in the usual manner and attached by brake-levers 4 to the opposite brake-beams 5 of each truck, said beams carrying shoes 6, as in the ordinary brake construction. The brake mechanism carried by the trucks is essentially of the usual form of such devices and need not be particularly described, it being understood that drawing tension exerted on one end of each of the arms 3 in a certain direction will cause both brake-beams 5 and their shoes 6 to be drawn simultaneously against the wheels of each truck, and when the arm is released the parts will be restored to normal position or so that the brake-shoes will hang clear of the truck-wheels, the release operation being facilitated by the interposition of a spring 7 between the arm 3 and the adjacent part of the truck on which the plate 1 is secured.

The gist of the invention resides in an intermediate rotary controller or leverage multiplier 8, which in the present instance comprises a horizontally-disposed double drum 9 or a drum provided with two sepa-

- rate winding-surfaces 10 and 11 by an intermediate circumferential flange 12. This drum has upper and lower trunnions 13, rotatably held in the upper and lower members of a slide or shifting carrier 14, the upper member of the latter engaging side guides 15 at the lower terminals of a hanger 16, which is secured to the under side of the bed of the car or to the framework beneath the latter, 5
- 10 in accordance with the particular car construction to which the brake is applied. Radially disposed with respect to the upper and lower heads of the drums and arranged in reverse positions are guards 17, and in the said 15 guards longitudinal slots 18 are formed in alignment with similar slots 18^a in the heads of the drum. The slots 18 and 18^a are engaged by rollers 19, which travel therein, and connected by a spindle 20, the said rollers, 20 respectively, having upper and lower flanges 21 of greater diameter than the width of the slots to bear against the upper and lower sides of the guards and the drum-heads, as clearly shown by Fig. 3. The purpose of the 25 flanged rollers is to reduce friction in the operation thereof and prevent them from becoming displaced or thrown out of engagement with respect to the guards and drum-heads. In other words, it is desired that the 30 connected rollers be maintained at all times in normal position irrespective of the pulling strain that may be applied thereto and which will be more fully hereinafter explained. Each of the spindles 20 has an arm 22 applied 35 thereto and projected diametrically in opposite directions, the arms being held in planes at right angles to the lengths of the slots 18 and 18^a and also serve as a further means to prevent displacement of the rollers 19.
- 40 Each of the brake-staffs 23, located at opposite ends of the car-body, has in addition to the lower ratchet or locking wheel 24 a lower involute winding-head 25 with a base-flange 26, and to said head is attached the 45 outer end of the brake-operating chain or analogous device 27, the opposite end of said chain being attached to one of the winding-spaces of the drum 9. The chains or analogous devices 27 extending inwardly from the 50 opposite brake-staffs pass over diametrically opposite portions of the drum 9 and wind and unwind in reverse directions with respect to the drum in the separated spaces of the latter, and by the operation of either brake-staff 55 to apply the brakes the brake mechanism of both trucks will be simultaneously operated.
- Attached to the free ends of the arms 3 are the outer terminals of brake-rods 28, having 60 intermediate turnbuckles 29 to take up unnecessary slack and compensate for wear of the brake-shoes. To the inner ends of the 65 brake-rods 28 chain-couplings or other flexible devices 30 are secured and also attached to the outer ends of the arms 22, and

by this means the rotation of the drum 9 or the actuation of the controller will be transmitted through the rods 28 and actuate the brake mechanism either in the applying or releasing operations of the latter. 70

The rollers 19, conjointly operating, may be correctly termed "leverage multipliers or multiplying means," for when either of the chains or analogous devices 27 is operated to apply the brakes the rollers are forced toward 75 the center of the controller from opposite directions and quickly take up the slack and at the same time increase the leverage on the brake mechanism directly carried by the trucks through the rods 28 and flexible connections 30. Owing to the movable attachment of the connections 30 to the controller through the medium of the rollers, the intensified tension desired to be set up in the rods 28 will immediately ensue without lost motion in view of the opposite positions of the rollers and the rotation of the controller, and any tendency toward twisting the rollers out of place would be resisted by the flanges 21 and the arms 22. Though the flanges 21 85 and arms 22 will resist disarrangement or disengagement of the rollers 19, they will not interfere with the antifrictional operation of such rollers, and the latter will always be sensitive to movement. 90

In Figs. 5 and 7 a modification of the leverage-multiplying means is shown, the roller heretofore explained being dispensed with and in lieu thereof reversely-arranged involute heads 31 are attached to the centers of 100 the opposite heads of the drum, and to the bases of said heads the connections 30 are attached and wind in opposite directions on said heads. As the connections 30 traverse the heads 31 from the bases toward the reduced portions of the heads, the leverage is gradually increased by bringing said connections nearer to the center of the drum. In other respects the devices shown by Figs. 7 and 8 are in all particulars similar to the construction heretofore explained, and like reference-notations are applied thereto. 105

The involute heads at the lower terminals of the brake-staffs 23 are also beneficial in the operation of the brake in that in the preliminary or primal rotation of either staff a greater portion of the chain 27 will be taken up and the controller 8 more rapidly actuated to quickly bring the brake mechanism in braking relation to the truck-wheels with 110 less effort on the part of the motorman or operator and also more uniformly and readily take up the slack of the chains or other connections 27.

The movement of the controller in opposite longitudinal directions, through the medium of the guide construction heretofore explained, compensates for wear and is also important when a car is rounding a curve and one truck passes onto the arc before the 115 130

other reaches the same or in making a switch. Under these conditions the controller yields or gives way proportionately to the irregular position of the trucks with relation to each other without blocking or interfering with the movement of the latter.

From the foregoing it will be seen that a very powerful yet easily-operated brake mechanism is provided and which will insure a forceful application of the brake-shoes to the truck-wheels.

By the use of the improved hand-brake mechanism herein disclosed the vibration and injury to the general car structure is reduced to a minimum, and, further, in view of the positive operation of the several parts set forth a car may be stopped, under normal conditions, within a shorter distance from the time the initial operation to apply the brakes is pursued than is possible in the ordinary brake structures.

Having thus fully described the invention, what is claimed as new is—

1. In a car-brake mechanism, trucks provided with brake devices, brake-staffs, a carrier movably mounted, a drum provided with slots and independent winding-surfaces and rotatably mounted upon the carrier, leverage-multiplying means movable in said slots, and connections between the brake-staffs and said winding-surfaces and between the leverage-multiplying means and said brake devices.

2. In a car-brake mechanism, trucks provided with brake devices, brake-staffs provided with involute winding-heads, a carrier movably mounted, a controller journaled on said carrier, and connections between the said involute heads and controller and between the controller and said brake devices.

3. In a car-brake mechanism, trucks provided with brake devices, guides, brake-staffs provided with involute winding-heads, a carrier movably mounted on said guides, a controller journaled on said carrier and provided with slots and independent winding-surfaces, guards secured to the controller and provided with slots in alinement with the slots in the controller, spindles provided with rollers and movable in said slots, and connections between the winding-surfaces and involute heads and between the spindles and brake devices.

4. In a car-brake mechanism, trucks provided with brake devices, brake-staffs, a drum provided with slots and independent winding-surfaces, leverage-multiplying means movable in said slots, and connections between the brake-staffs and said winding-surfaces and between the leverage-multiplying means and said brake devices.

5. In a car-brake mechanism, trucks provided with brake devices, brake-staffs, a carrier movably mounted, a controller journaled

upon the carrier, and connections between the brake-staffs and controller and between the controller and brake devices.

6. In a car-brake mechanism, trucks provided with brake devices, brake-staffs, a controller having slots, guards secured to the controller and having slots in alinement with the slots in the controller, leverage-multiplying means movable in said slots, and connections between the controller and brake-staffs and between the leverage-multiplying means and brake devices.

7. In a car-brake mechanism, trucks provided with brake devices, brake-staffs, a controller having slots, leverage-multiplying means mounted in said slots, and connections between the controller and brake-staffs and between the leverage-multiplying means and brake devices, said leverage-multiplying means operating in said slots to draw the connections engaging the same closer to the center of the controller when the brakes are applied.

8. In a car-brake mechanism, trucks provided with brake devices, brake-staffs, a controller having radial slots, leverage-multiplying means movable in said slots, and connections between the controller and brake-staffs and between the leverage-multiplying means and brake devices.

9. In a car-brake mechanism, trucks provided with brake devices, brake-staffs, a controller having radial slots, leverage-multiplying means movable in said slots, a carrier supporting said controller, said carrier being movable longitudinally whereby to compensate for the irregular relative position of the trucks, and connections between the controller and brake-staffs and between the leverage-multiplying means and brake devices.

10. In a car-brake mechanism, trucks provided with brake devices, brake-staffs, a controller movably mounted whereby to compensate for the irregular relative positions of the trucks, said controller being provided with radial slots, leverage-multiplying means movable in said slots, and connections between the controller and brake-staffs and between the leverage-multiplying means and brake devices.

11. In a car-brake mechanism, trucks provided with brake devices, brake-staffs, a controller provided with radial slots and movable longitudinally whereby to compensate for the irregular relative positions of the trucks, leverage-multiplying means movable in said slots, and connections between the controller and brake-staffs and between the leverage-multiplying means and brake devices.

12. In a car-brake mechanism, trucks provided with brake devices, brake-staffs, a carrier movably mounted, a controller rotatably mounted upon the carrier and provided with

leverage - multiplying means, and connections between the controller and brake-staffs and between the leverage-multiplying means and brake devices.

5 13. In a car-brake mechanism, trucks provided with brake devices, brake-staffs, a carrier mounted upon the car to have a longitudinal movement, a controller rotatably mounted upon the carrier and provided with leverage - multiplying means, and connections between the controller and brake-staffs and between the leverage-multiplying means and brake devices.

14. In a car-brake mechanism, trucks provided with brake devices, brake-staffs, a carrier movably mounted, a drum provided with slots and rotatably mounted upon the carrier, leverage-multiplying means mounted in said slots, and connections between the controller and brake-staffs and between the leverage-multiplying means and brake devices.

15 15. In a car-brake mechanism, trucks provided with brake devices, brake-staffs, a carrier movably mounted, a drum provided with slots and rotatably mounted upon the carrier, leverage-multiplying means mounted in said slots, and connections between the controller and brake-staffs and between the leverage-multiplying means and brake devices.

16. In a car-brake mechanism, trucks provided with brake devices, brake-staffs, a rotatably-mounted controller having slots, leverage-multiplying means mounted in said slots, and connections between the controller and brake-staffs and between the leverage-multiplying means and brake devices.

and brake-staffs and between the spindles and brake devices.

16. In a car-brake mechanism, trucks provided with brake devices, brake-staffs, guides, a carrier movably mounted on the guides, a drum provided with slots and rotatably mounted upon the carrier, guards secured to the drum and provided with slots in alignment with the slots in the drum, spindles provided with rollers mounted in said slots, and connections between the drum and brake-staffs and between the spindles and brake devices.

17. In a car-brake mechanism, trucks provided with brake devices, brake-staffs, a rotatably-mounted controller having slots, leverage-multiplying means mounted in said slots, and connections between the controller and brake-staffs and between the leverage-multiplying means and brake devices.

In testimony whereof I affix my signature in presence of two witnesses.

CHARLES A. FISHER.
